UNITED STATES PATENT OFFICE.

ELMORE M. GODFREY, JR., OF KNOXVILLE, TENNESSEE.

WORKTABLE FOR PNEUMATIC-TIRE REPAIRING.

Application filed February 23, 1927. Serial No. 170,375.

This invention relates particularly to an improved work table intended especially for use by persons engaged in mending pneumatic tires, either the casings or the inner tubes of such tires.

The object of the invention is to produce such a work table in compact and convenient form embodying means for facilitating the various steps or operations concerned with the mending of such tires.

In the accompanying drawings,

Fig. 1 is an elevation of a structure embodying my improvement;

Fig. 2 is an elevation of the structure looking at Fig. 1 from the right;

Fig. 3 is a horizontal section on the line, 3—3, of Fig. 2;

Fig. 4 is an upright section on the line, 4—4, of Fig. 1, looking toward the right;

Fig. 5 is a horizontal section on the line, 5—5, of Fig. 2;

Fig. 6 is a section on the line, 6—6, of Fig. 2, looking upward;

Fig. 7 is a horizontal section on the line, 7—7, of Fig. 4.

Referring to the drawings, A is a base adapted to rest on and be secured to a floor. A² is a tubular column rising from said base and open at its upper end and having in the upper edge of its wall four notches, A².

A lower stem, B, is telescoped slidably and rotatably into the column, A¹. On the upper end of the stem, B, is a head, B², on which is supported the table top, C, in which is a bushing, C¹, having an upper horizontal flange. The lower stem, B, has two radial stub pins, B¹, which normally rest in two diametrically opposite notches, A². To per-

mit turning the table, the stem, B, is to be raised in the column, A, to bring the stub pins, B¹, above the notches, A². That raising is accomplished by means of a foot lever, A³, fulcrumed at A⁴ to the column, A¹. An

upright lifting rod, A⁵, has its lower end coupled to the rear end of the lever, A³. That rod extends slidably through a sleeve, A⁶, on a bracket, A⁷, fixed on the column, A. The upper end of said rod is bent

laterally and formed into a horizontal arm, A⁸, extending around or partially around the stem, B, close to the lower part of the head, B², of the stem, B. By depressing the free end of the foot lever, the lifting rod, A⁵,

is pushed upward, whereby the arm, A⁸, is made to lift the head, B², and the stem, B,

whereby the table and all parts supported by the table and also the upper stem, D, are lifted. Then the table top, C, may be engaged by the hand of the operator for turning the table top and parts associated therewith.

The upper stem, D, extends downward through the bushing, C¹, and is threaded through the head, B², and extends into the stem, B, below said head. By turning the stem, D, its height in the stem, B, and relative to the table top, C, may be varied. Above the table a hand wheel, D¹, surrounds and is keyed to the stem, D. Said wheel is to be grasped by the hands of the operator for turning said stem. Immediately above the bushing, C¹, the upper stem, D, is surrounded by a jam nut, D², on which is a hand wheel, D³. When the stem, D, has been turned to bring it to the desired height, the hand wheel, D³, is to be turned in the proper direction to drive the jam nut, D², down against the bushing, C¹, for jamming the threads on the stem, D. The hand wheel, D¹, has its hub directed upward. Above said hub and resting thereon, a circular tool tray, D⁴, loosely surrounds the upper stem, D, and is rotatable on said stem while resting on said hub.

In the upper end of the upper stem, D, is an upright socket, D⁵, on the axial line of said stem and opening upward. A metal arm, D⁶, has on one end a finger, D⁷, resting rotatably in said socket for the support of said arm. The other end of said arm is in the form of a hook, D⁸, which is approximately in a line rising from the edge of the table top.

In the form shown by the drawings, the table top, C, is made of wooden boards having their edges fitted or glued together. On the under face of the top are two transverse reinforcing strips of wood, C³, suitably secured to the top, as by means of screws or nails. A pair of parallel tire supports, C⁴, are applied slidably to the lower face of the top. These are in the form of metal rods slidable in one of the binding strips, B³, and in one of the guide strips, C⁵, secured to the lower face of the top. The two supports, C⁴, are shown joined by a transverse member, C⁶, which is located between the adjacent binding strip, C³, and the guides, C⁵. The space between the members, C³ and C⁵, is sufficient to allow the joining member, C⁶, to move far enough outward and

inward to bring the outer ends of the members, C⁴, outward beyond the edge of the table top as far as desired, and to bring the outer ends of the members, C⁴, close to said edge when said members are not being used. The outer or free ends of the members, C⁴, are turned up slightly or to any desired extent for the purpose of holding the tire, as will be described further on.

At the edge of the table top opposite the edge from which the members, C⁴, project, a pair of brackets, E, are secured to the lower face of the top, C, and made to project outward a short distance beyond the edge of the top. On each of said brackets is supported a standard, E¹. Between the upper ends of said standards is a form, E², each end of the form being attached to the end of the adjacent standard. Said form is approximately the shape of a segment of a pneumatic tire casing, the form being in an upright plane and the axis of the circle in which the form lies being below the form.

On the under face of the table top is a plate, F, applied flatwise to the top and pivoted thereto at F¹ to turn in a horizontal plane. This plate may be folded under the table top or extended outward perpendicularly to the adjacent edge of said top. A guide member, F², engages the plate when the latter is in the outer position, the guide member and the hinge member together supporting the plate. Said plate is to be used for supporting the inner tube of the pneumatic tire while said tube is being mended.

This work table is adapted to the several operations already mentioned. For working on the inner part of a pneumatic tire casing, said casing is hung on the arm, D⁶, while the lower part of the casing rests on the pair of supports, C⁴. The finger, D⁷, is rotatable in the socket, D⁵, of the upper stem, D. This allows turning the arm, D⁶, to the working position after the stem, D, has been turned to vary its height to change the elevation of said arm as may be necessary for tire casings of different sizes.

When the exterior of the casing is to be mended, the casing is to be hung on the form E², the form being placed inside the casing. By rotating the table, the operator may, without changing position, bring said form, E², or the pair of supports, C⁴, or the plate, F, to the operator. Furthermore, if the operator desires to change position to have better light on his work, he can make that change and then turn the table top to bring the desired working part or parts before him. The inter-engagement between the tubular column, A¹, and the lower stem, B, is to be of sufficient strength to prevent turning of the table top when such turning is not desired.

The tool tray, D⁴, is conveniently located for holding all the tools ordinarily needed

in this work. And because said tray is rotatable, it may be turned independently of the table top and independently of the upper stem, D, to bring any part of said tray in front of the operator.

It will be seen that this structure is compact and will occupy small space. In such a structure which I have built and put into daily use, the horizontal dimensions of the top are 22 inches by 26 inches. That size is ample.

I claim as my invention:

1. In a structure of the kind described, the combination of a tubular column, a stem telescoping and rotatable in said column and said stem and column being formed for inter-engagement in any of a plurality of positions into which the stem may be turned, operator-controlled means for lifting said stem, and a table top supported by said stem.

2. In a structure of the kind described, the combination of a tubular column, a stem telescoping and rotatable in said column and said stem and said column being formed for inter-engagement in any of a plurality of positions into which the stem may be turned, a foot lever, means in operative relation with said lever and with said stem for lifting said stem, and a table top supported by said stem.

3. In a structure of the kind described, the combination with a table top and an under structure supporting the table top rotatably, of an upper structure comprising a stem above the table top and a lateral arm adapted to support a pneumatic tire casing.

4. In a structure of the kind described, the combination with a table top and an under structure supporting the table top rotatably, of an upper structure comprising a stem adjustable up and down above the table top and a lateral arm adapted to support a pneumatic tire casing.

5. In a structure of the kind described, the combination with a table top of an under structure comprising a stationary tubular column and a stem rotatable in said column and having its upper end attached to the lower face of the table top, and an upper structure comprising a stem above the table top and a lateral arm adapted to support a pneumatic tire casing.

6. In a structure of the kind described, the combination of a table top, an under structure comprising a stationary tubular column and a stem rotatable in said column the column and the stem being formed for inter-engagement in any of a plurality of positions into which the stem may be turned, and the stem having its upper end attached to the lower face of the table top, and an upper structure comprising a stem above the table top and a lateral arm adapted to support a pneumatic tire casing.

7. In a structure of the kind described, the combination of a tubular column, a stem telescoping and rotatable in said column and said stem and said column being formed for 5 inter-engagement in any of a plurality of positions into which the stem may be turned, operator-controlled means for lifting said stem, a table top supported by said stem, an upper stem supported by said lower stem, 10 and an arm extending laterally from the upper end of the upper stem and having its outer end hook-form.

8. In a structure of the kind described, the combination of a tubular column, a stem telescoping and rotatable in said column and said stem and said column being formed for 15 inter-engagement in any of a plurality of positions into which the stem is turned, operator-controlled means for lifting said stem, 20 a table top supported by said stem, an upper stem supported by said lower stem, an arm extending laterally from the upper end of the upper stem and having its outer end hook-form, and means on the table top for 25 supporting the lower part of a tire casing.

9. In a structure of the kind described, the combination with a table top and an under structure supporting said top, of a pair of tire supporting members at one edge 30 of the table top.

10. In a structure of the kind described, the combination with a table top and an under structure supporting said top, of a pair of 35 slideable tire supporting members at one edge of the table top.

11. In a structure of the kind described, the combination with a table top having 40 guide members and an under structure supporting said top, of a pair of tire supporting members at one edge of the table top and slideable in said guide members.

12. In a structure of the kind described,

the combination with a table top having 45 guide members and an under structure supporting said top, of a pair of tire supporting members at one edge of the table top and slideable in said members, and a transverse member joining said guide members.

13. In a structure of the kind described, the combination with a table top having 50 guide members and an under structure supporting said top, of a pair of tire supporting members at one edge of the table top and slideable in said members, and a transverse member joining said guide members between 55 the guide members.

14. In a structure of the kind described, the combination of a tubular column, a lower stem telescoping and rotatable in said 60 column, a table top supported by said stem, an upper stem screw-threaded to the lower stem, and an arm extending laterally from the upper end of the upper stem.

15. In a structure of the kind described, the combination of a tubular column, a lower stem telescoping and rotatable in said 65 column, a table top supported by said stem, an upper stem screw-threaded to the lower stem, and an arm extending laterally from the upper end of the upper stem and turnable on said stem. 70

16. In a structure of the kind described, the combination of a tubular column, a lower stem telescoping and rotatable in said column, a table top supported by said stem, 75 an upper stem screw-threaded to the lower stem, a jam nut on the upper stem, and an arm extending laterally from the upper end of the upper stem.

In testimony whereof I have signed my 80 name this 21st day of February, in the year one thousand nine hundred and twenty-seven.

ELMORE M. GODFREY, JR.
